MIXING DEVICE

Filed Aug. 14, 1930

UNITED STATES PATENT OFFICE

HERBERT RYAN TUMIM, OF BUFFALO, NEW YORK, ASSIGNOR TO NATIONAL ANILINE & CHEMICAL CO., INC., OF NEW YORK, N. Y., A CORPORATION OF NEW YORK

MIXING DEVICE

Application filed August 14, 1930. Serial No. 475,196.

This invention relates to mixing apparatus of the rotary drum type and relates particularly to improvements in the construction of such apparatus to adapt the same for the blending or mixing of dry powders without dusting and for discharging the mixed powders from the mixing chamber.

It is an object of the present invention to provide a rotary mixer having a discharging hopper which is fixed during the discharging operation, and wherein provision is made for misalignment of the rotary mixer and discharging hopper. It is also an object to provide an apparatus of the character described wherein the discharging hopper is rotatable with the rotary mixer during the mixing operation, whereby the life of the operative connection between the said parts is prolonged. A further object is the provision of a closure which is simple in construction and operation for the rotary mixer to prevent dusting of the contents. Other objects will be apparent from a consideration of the following disclosure.

In accordance with the present invention the mixer comprises a rotary mixing chamber having a discharging hopper which may be rotated therewith during the mixing operation. The discharge hopper may be rotated by the mixing chamber through a suitable operative connection or it may be rotated by independent operative means. Means are provided for maintaining the discharging hopper stationary while the mixing chamber is rotated during the discharging operation to discharge its contents. If desired, a closure may be provided for the discharge opening of the mixing chamber to prevent dusting of material. A movable chute, scoop or other suitable device directs the discharge of material through the discharging opening in the mixing chamber and the discharge hopper.

In order that my invention will be more clearly understood, reference is made to the drawing which illustrate a preferred embodiment of my invention and in which

Figure 1 is a sectional view of the discharging device in position on a rotary mixer; Figure 2 is a sectional view taken at right angles

to Figure 1 on the line 2-2; and Figures 3 and 4 illustrate modifications of details of the apparatus.

In the form of the invention illustrated in the drawing the apparatus comprises a mixing chamber or drum 2 which may be rotated by a pinion coaxing with a spur gear mounted on the drum (not shown) and is supported upon the idling rollers 4 which engage the guide ring or track 6 secured to the periphery of the mixing chamber. The discharge end 1 of the mixing drum has its central portion cut away to provide a hole 3 for receiving a cover plate 8 having a central discharge opening 10 therein. The cover plate 8 is provided with a flared collar 12 which extends outwardly from the opening 10 to provide a tapered seat 5 on its inner surface for the closure 40, which will be described hereinafter in greater detail, and allows delivery of the discharging material from the discharge opening 10 in the mixing chamber to the discharging hopper 14.

An annular bronze wear plate or journal 20 is suitably secured to the extremity 7 of the collar 12. The discharge hopper comprises a drum shaped hollow head 14 having a centrally located opening 9 in one end thereof adapted to register with the mouth 11 of the collar 12. The opening 9 is surrounded by an annular step 13. The discharge hopper 14 is carried by the collar 12 and is retained in place by the annular retaining plate 18 which is suitably secured to the step 13 on the discharge hopper 14. The retaining plate 18 extends inwardly to encircle the extremity 7 of the collar 12 and bears against the wear plate 20. A packing chamber 15 is rabbeted in the wall of the opening 9 to receive a gasket or packing ring 22, which bears against the wear plate 20 to prevent access of foreign matter thereto. A dust apron or sleeve 24 is secured to the interior face of the collar 12 and projects over the packing ring 22 and opening 9 in the discharge hopper 14 to protect these parts against entrance of foreign matter thereto. A discharge opening 16 in the head 14 communicates with the central opening 9 in the

head 14 to permit discharge of material from the apparatus.

The opening 10 in the cover plate 8 may be closed by the closure 40 having a tapered face 17 which bears against the tapered seat 5 in the collar 12. The closure 40 has its central portion thickened to form a hub 26 which is bored at 19 and counterbored at 21 to permit insertion of the flanged bushing 42 which is tightly wedged into bore 19 or otherwise fastened to hub 26 to rotate therewith. A shaft 30 extending at one end 23 through the bushing 42 is freely rotatable therein and has its other end threaded at 32. A gasket 25 is pressed against the face of the flange 27 of the bushing 42 by a plate or washer 29 held in place by a nut 31 threaded on the end 23 of the shaft 30, and held against rotation by a locking pin 28 which prevents the entrance of foreign matter between the shaft 30 and bushing 42. It is therefore evident that the closure 40 with its bushing 42 is capable of free rotation on the shaft 30. The end wall 33 of the head 14 has a thickened portion 34 which is bored and threaded at 37 to receive the thread end 32 of the shaft 30. The end 23 of the shaft 30 is rigidly secured to a hollow shaft 44 by coupling pins 46 and extends through the drum 2 and is rotatably held at its other end by suitable means not shown. A discharge chute or scoop 48 has a thickened hub portion 39 through which passes the hollow shaft 44 which is rigidly secured thereto by pins 41. A hand wheel 36 for operating the shaft 30 is suitably secured to the threaded end 32 of the shaft 30, and a lock nut 38 is carried by the shaft for locking the shaft and hopper in fixed relationship.

In operation the head 14 is in operative engagement with the collar 12 through the yielding operative connection comprising the sleeve 24, packing 22, retaining plate 18 and wear plate 20, and during the mixing operation the head 14 is permitted to rotate in unison with the mixing drum 2.

In mixing position the closure 40 will be retained in its seat 5 by pressure exerted 50 through the screw 32 coacting with the threaded bore 37 in the end wall 33 in the head 14, and which is held against rotation relative to the head 14 by the lock nut 38 on the shaft 30 turned to bear tightly against the thickened abutment 34 in the end wall 33. The hollow shaft 44 being rigidly connected to the shaft 30, will rotate therewith and thereby revolve the discharge scoop 48 about the hollow shaft 44 with which it is 60 rigidly connected.

When the mixed or blended powder is ready to be discharged the rotation of the drum 2 is stopped in such position by the operative that the discharge opening 16 is 65 turned downward. The discharge head 14

has one or more lugs 52 projecting from the side thereof which have a hole 43 bored therein to receive a locking pin 54. In discharging position, the lug 52 is adapted to be engaged by a toggle link 50 forked at one end to embrace the lug 52 and having the holes 47 and 49 in its prongs to register with the hole 43 in the lug 52. The opposite end of the toggle link 50 is hinged in a suitable manner to a second toggle link (not shown) which in turn is pivoted to the frame of the machine. The toggle link 50 is locked to the lug 52 by the locking pin 54 which passes through the holes 47 and 49 in the toggle link 50 and the hole 43 in the lug 52 to hold the discharge head against rotation. The mixing drum is now set in motion by the operative. Because the operative connection between the head 14 and drum 2 depends only on frictional engagement of the compressed packing 22 against the sleeve 24, the drum 2 is capable of rotation free of the discharge head. In this position, the closure 40 which is held in frictional engagement with the seat 5 will rotate with the drum about the shaft 30, which is locked against rotation by the lock nut 38 coacting with the abutment 34. Of course, it will be understood that if desired, the mixing operation may be carried out in this position, but since relative motion of rotating drum 2 and fixed discharge hopper 14 will result in wear on the packing 22, this practice should be avoided as much as possible.

To discharge the contents of the drum the lock nut 38 is turned back slightly to release the shaft 30, and by turning the hand wheel 36 the operative may retract the shaft 30, carrying the closure 40 out of contact with its seat 5 and bringing the lower edge of the scoop 48 into proximity with the discharge opening 10, as shown in dotted lines in Figure 1.

Since the scoop 48 rotates with the shaft 30 a suitable marker may be placed on the hand wheel 36 to show the operative when the scoop is in discharging position. The closure 40 is locked in open position and the chute 48 is locked in discharging position by turning the locking nut 38 against the abutment 34. The vanes in the drum 2 will carry material to the top of the drum as the drum rotates from whence it will drop into the scoop 48 and be directed through the opening 10 and through the opening 16 into a suitable receptacle.

The discharge hopper 14 may be used for charging the drum 2, or a separate manhole may be provided in the drum for this purpose. For mixing materials in which dusting is not objectionable the closure 40 may be omitted, if desired, or the apparatus may be operated with the closure open and the discharge scoop 48 in inverted position.

In the modification shown in Figure 3, the

end wall 33 has a thickened portion 51 which is bored at 53 to receive the shaft 30 and is counterbored at 55 to receive the bushing 56 through which the shaft 30 passes. A spider 50 on the wall 33 carries an abutment 58 having a threaded bore 57 therein for coacting with the thread 32 on the shaft 30.

An alternative connection between the discharge hopper 14 and the collar 12 is shown in Figure 4. The packing chamber 15, instead of being in the face of the opening 9 as shown in Figure 1, lies in the step 13. The packing 62 is compressed by the retaining plate 18 against the wear plate 20 instead of being compressed against the sleeve 24 as shown in Figure 1.

The form of the apparatus illustrated in the drawing is a preferred embodiment of my invention shown in relationship with a mixing device of conventional design, and it is not intended that the invention should be limited to the specific device shown and described, except as defined by the claims.

I claim:

1. The combination comprising a rotatable mixing chamber having a discharge opening at one end thereof providing a seat for a closure, a closure seated in the discharge opening and rotatable therewith, a discharge hopper communicating with said opening and normally rotatable with the mixing chamber, and means to hold said discharge hopper in fixed position while the mixing chamber and closure rotate.

2. The combination comprising a rotatable mixing chamber having a discharge opening at one end thereof providing a closure seat, a closure seated in the discharge opening and rotatable therewith, a member rotatable with said mixing chamber supporting said closure, means for holding said member in fixed position while said chamber and closure rotate, and means for moving the closure axially of the mixing chamber into or out of engagement with the closure seat while the mixing chamber rotates.

3. The combination comprising a rotatable mixing chamber having a discharge opening at one end thereof formed to provide a closure seat, a closure seated in the closure seat and rotatable therewith, supporting means rotatable with the mixing chamber to support the closure and retain the closure in the seat, means to hold the supporting means in fixed position while the mixing chamber and closure rotate, and means for moving the closure into or out of engagement with the closure seat while the mixing chamber rotates.

4. The combination comprising a rotatable mixing chamber having a discharge opening at one end thereof, a discharge hopper carried by the mixing chamber in communication with the discharge opening, a closure supported by the discharge hopper and ro-

tatable with said mixing chamber, means to hold the discharge hopper in fixed position while the mixing chamber rotates, and means for moving the closure in or out of engagement with the discharge opening while the mixing chamber rotates.

5. A mixing apparatus comprising a rotatable mixing drum having an opening in one end thereof, a discharge hopper, carried by said drum and rotatable therewith communicating with said opening, a shaft extending through said opening, a chute within said drum secured to said shaft and movable therewith to direct material from the drum through the discharge opening, and means for holding said discharge hopper in a fixed position while said drum continues to rotate.

6. A mixing apparatus comprising a rotatable mixing drum having a discharge opening in one end thereof, a discharge hopper carried by the drum and rotatable therewith communicating with said opening, a shaft extending axially through said opening and mounted in the discharge hopper, a discharging scoop within the drum and secured to said shaft, a closure for said opening mounted on said shaft and rotatable with said drum, means for holding the discharge hopper in a fixed position while said drum rotates, and means for moving said shaft axially to move said closure in and out of closing position and to move said scoop in and out of discharging position.

7. A mixing apparatus having in combination a rotatable drum having a discharge opening in one end thereof, a discharge hopper carried by the drum communicating with the discharge opening, a yielding operative connection between the drum and said hopper to cause said hopper to rotate with the drum, means for holding said discharge hopper stationary while the drum rotates, and a discharge scoop within the drum and carried by the discharge hopper for directing the discharge of material through said opening.

8. A mixing apparatus having in combination a rotatable drum having a discharge opening in one end thereof, a discharge hopper carried by the drum and communicating with the discharge opening, a yielding operative connection between the drum and said hopper to cause said hopper to rotate with the drum, means for causing said operative connection to yield to hold said hopper stationary while the drum rotates, a discharge scoop within the drum to direct the discharge of material through said opening, supporting means carried by said hopper for supporting the scoop, and means for moving said scoop and supporting means into and out of discharging position.

9. A mixing apparatus comprising a horizontal rotatable drum having a coaxial discharge opening in one end thereof, a support

- ing collar surrounding said opening, a discharge hopper carried by said collar and operatively connected thereto by a yielding connection, a closure seated in said discharge opening and rotatable with said drum, supporting means for said closure locked to rotate with said discharge hopper, and means to cause said yielding connection to yield.
10. A mixing device comprising a mixing chamber in the form of a horizontal rotatable cylinder, a flared collar secured to one end of the cylinder and provided with an opening positioned axially of the cylinder, a discharge hopper carried by said collar rotatable with said cylinder and mounted for rotation with reference to said collar, means for preventing the passage of material between said collar and discharge hopper, and means for holding the discharge hopper stationary while said cylinder continues to rotate.
11. A mixing device comprising a mixing chamber in the form of a horizontal rotatable cylinder, a flared collar secured to one end of the cylinder and provided with an opening positioned axially of the cylinder, a discharge hopper carried by said collar rotatable with said cylinder and mounted for rotation with reference to said collar, means for preventing the passage of material between said collar and discharge hopper, a shaft secured to said discharge hopper and extending axially through said opening, and a closure for said opening mounted on said shaft and rotatable with said cylinder.
12. A mixing device comprising a rotatable mixing chamber having a lateral discharge opening therein, a discharge hopper in alignment with the discharge opening and rotatable relative thereto, means for coupling the discharge hopper to the mixing chamber to cause rotation in unison therewith, and a chute within the mixing chamber movable into and out of position to discharge material from said mixing chamber into said discharge hopper.
13. The combination which comprises a mixer having a discharge opening therein, a discharge hopper aligned with a discharge opening in the mixer positioned to receive material discharged from said mixer through said opening, said discharge hopper having a radially positioned outlet, means for permitting independent rotation of said discharge hopper with respect to the mixer, and means for coupling the discharge hopper to the mixer to cause rotation in unison therewith.
14. The combination which comprises a mixer, a discharge hopper aligned with a discharge opening in the mixer, means for permitting independent rotation of said discharge hopper, a shaft passing axially through said hopper, a closure member mounted on said shaft, a chute mounted

on said shaft and within the mixer, means for imparting lateral movement to said shaft, and means for coupling the discharge hopper to the mixer to cause rotation in unison therewith.

15. The combination comprising a rotatable mixing chamber having a discharge opening therein, a discharge hopper carried by the mixing chamber and rotatable therewith, means within the mixing chamber to direct material through the discharge opening, supporting means for said first mentioned means carried by the discharge hopper, means for locking said supporting means for rotation with said hopper, and means for holding said hopper in fixed position while the mixing chamber rotates.

16. The combination comprising a rotatable mixing chamber having a discharge opening therein, a discharge hopper positioned to receive material discharged from said mixing chamber through said opening, said hopper being carried by the mixing chamber and normally rotatable therewith, a discharge scoop carried in the mixing chamber, means rotatable relative to the discharge hopper for supporting the discharge scoop, and means for locking said first mentioned means to the discharge hopper to rotate therewith.

17. A mixing apparatus comprising a horizontal rotatable drum having an opening in one end thereof, a cover plate secured to the drum over said opening and having a discharge opening therein, a collar surrounding said discharge opening, a journal on said collar, a drum shaped discharge hopper having an opening in one end thereof registering with said discharge opening, a step on said discharge hopper surrounding said hopper opening, a retaining plate on said hopper to hold said hopper in position on said collar, a sleeve lining for said collar and said hopper opening, a yielding friction coupling between said sleeve and said hopper, and means for holding said hopper in fixed position while said drum rotates.

In witness whereof I have hereunto set my hand.

HERBERT RYAN TUMIM.
